(74) *Attorney, Agent, or Firm* — Dorsey & Whitney LLP

(57) **CLAIM**

The ornamental design for an automobile grille, toy replicas, and/or other replicas, as shown and described.

DESCRIPTION

FIG. 1 is a front perspective view of an automobile grille, toy replicas, and/or other replicas showing my new design; FIG. 2 is a right side elevation view thereof, the left side elevation view being a mirror image of the right side elevation view;

FIG. 3 is an enlarged front elevation view thereof; FIG. 4 is an enlarged front and right side perspective view thereof; and,

FIG. 5 is an enlarged front and left side perspective view thereof.

The broken lines illustrate environmental structure that forms no part of the claimed design.

1 Claim, 5 Drawing Sheets
